UNITED STATES PATENT OFFICE.

JOSEPH F. HOLMES, OF HUNTSVILLE, ALABAMA.

BANANA-SHIPPING DEVICE.

1,082,524.

Specification of Letters Patent.

Patented Dec. 30, 1913.

Application filed September 9, 1912. Serial No. 719,405.

To all whom it may concern:

Be it known that I, JOSEPH F. HOLMES, a citizen of the United States, residing at Huntsville, in the county of Madison and 5 State of Alabama, have invented certain new and useful Improvements in Banana-Shipping Devices, of which the following is a specification.

My invention relates to devices for shipping bananas and like fruit and has for one 10 of its objects the provision of a collapsible frame having means for supporting the bunches of bananas, said frame being so constructed that it may be assembled together 15 with other frames to economically and completely fill a car or a ship's hold.

My invention will be described in detail hereinafter and illustrated in the accompanying drawings, in which,

20 Figure 1 is a top plan view of one of my improved shipping devices showing it as a part of a system of devices; Fig. 2, a side view of my invention showing it superposed on the fragment of another device; Fig. 3, 25 an end view; Fig. 4, an end view showing one of the devices collapsed; Fig. 5, a fragmental cross section on the plane indicated by the line 5—5 of Fig. 3; Fig. 6, a similar view on the plane indicated by the line 6—6 30 of Fig. 3; and Fig. 7, a detail of the lower end of one of the supporting arms.

In the drawings similar reference characters will be used to designate corresponding parts throughout the several views.

35 My improved banana shipping device comprises a collapsible frame having its ends formed by crossed rods indicated at 1 that are pivotally secured intermediate of their ends as shown at 2. Each pair of 40 crossed rods 1 are connected at their upper ends by longitudinal rods 3 and at their lower ends by means of longitudinal rods 4 said rods 4 being shorter than the rods 3 for the purpose to be hereinafter described.

45 Secured near the upper terminal of each rod 1 is a bar 5, said bars being pivotally secured together as shown at 6 and one of said bars provided with a hook-shaped flange 7, said pivotally connected bars acting 50 as braces to hold the upper ends of said bars in a distended position as shown in Figs. 1, 2 and 3. Pivotally secured adjacent to the lower terminals of the bars 1 are other rods 8, said rods 1 being pivotally secured together as shown at 9, and one of 55 said bars is also provided with a hook-

shaped flange 10 to limit the movement of said bars, said bars 8 acting as braces to hold the lower ends of said rods 1 in a distended position.

60 11 indicates a sling of any suitable fabric such as burlap that is secured at two of its margins to the rods 3 and when the device is in an extended position as shown in Figs. 1, 2 and 3, serves to hold bunches of bananas 65 or other fruit or commodities therein.

65 The lower ends of the rods 1 are formed with angular extensions 12 that are provided with notches 13, said angular extensions 12 acting as feet for the device when in use and the notches 13 are adapted to engage the rods 3 so that a plurality of the devices may be assembled in superposed positions to economically fill a car or other 70 transporting means for the bananas or other 75 fruit, the rods 4 being as heretofore stated shorter than the rods 3 operate to cause the lower ends of the rods 1 to seat within the upper ends of said rods when superposed as heretofore stated.

80 One of each pair of bars 5 has its terminal that is pivotally connected to the rod 1 formed with a lateral flange 14 to which is secured a chain 15, while the corresponding terminal of the other of each pair of rods 5 is formed with an upwardly extending hook 16 that is adapted to engage the chain 15 on an adjacent device to connect the tiers of devices together when placed in position in the car or other means of transportation.

85 Having thus described my invention what I claim is:—

90 1. In a banana shipping device, angularly disposed supporting rods pivotally secured together intermediate of their ends, a plurality of horizontally arranged rods connecting said pivotally secured supporting rods in pairs, a fruit sling mounted on the said horizontally arranged rods connecting the upper 95 terminals of said pivotally secured rods, the lowermost terminals of said pivotally secured rods being formed with notches adapted to engage the upper horizontal connecting rods, spacing bars pivotally secured to said 100 pivotally secured rods adjacent to their upper ends, a chain secured to one of each pair of spacing bars, a hook formed on the other of each pair of rods, said bars being pivotally secured together and forming a brace 105 to hold the upper ends of said pivotally secured rods in a distended position, said chain 110

being adapted to have its free end secured to the said hook of the next adjacent shipping device when the structures are arranged in assembled position, spacing bars pivotally secured adjacent to the lower ends of said pivotally secured rods, and said spacing bars being pivotally secured together and adapted to act as a brace to hold the lower ends of said pivotally secured rods in a distended position.

2. In a banana shipping device a set of pivotally connected supporting legs, the lower terminals of each leg being angularly and inwardly directed with respect to the vertical plane of the pivotal point, the extreme terminals of said supporting legs being provided with substantially U-shaped slots, a plurality of horizontally arranged connecting rods secured at their ends to the corresponding terminals of the said supporting legs, a flexible sling secured to the upper of said connecting rods, a pair of spacing bars secured to each of said supporting legs, the said spacing bars having one end pivotally secured to a supporting leg, the said pairs of spacing rods being nor-

mally inwardly directed and pivotally secured at their contacting terminals, and a plurality of stop hooks carried by one of each of said spacing bars, a laterally extending perforated ear carried by one bar of each of said pairs of spacing bars and adjacent the fixed terminal thereof, a hook member carried by the other of each of said pairs of spacing bars, a plurality of connecting chains secured at one terminal to a perforated ear and adapted in the assembled position of the shipping devices to engage a hook member of the next adjacent device for maintaining the structures in the desired position; the said structures being adapted to the arrangement in series and to superposition, the slot portions of the legs of the superimposed structures being adapted to engage the upper horizontally disposed connecting rods of the adjacent lower structure.

In testimony whereof I affix my signature in presence of two witnesses.

JOSEPH F. HOLMES.
